IGNITER

Fred R. Belt, Chicago, Ill.

Application May 14, 1931. Serial No. 537,235

6 Claims. (Cl. 219—32)

This invention relates to igniters and particularly to that type used by smokers to ignite cigars, cigarettes, and the like.

It is among the objects of my invention to provide an electrically heated igniter which will be rendered operative as soon as it is lifted from the support on which it normally rests; which will embody a heating element that may be easily installed and removed; which will be equipped with a safety device to prevent inadvertent operation thereof; and which will be simple and economical in construction and positive in operation.

In the selected embodiment of the invention illustrated in the accompanying drawing

Fig. 1 is a top plan view;

Fig. 2 is a vertical sectional view taken substantially on the line 2—2 on Fig. 1;

Fig. 3 is a horizontal sectional view taken substantially on the line 3—3 on Fig. 2; and

Fig. 4 is a horizontal sectional view taken substantially on the line 4—4 on Fig. 2.

The igniter illustrated in the accompanying drawing includes a tubular casing 5 of insulating material, as for example that known as bakelite, and has a bore 6 slightly enlarged at one end as indicated at 7, and the casing includes a peripheral bead 8 adjacent this enlarged portion of the bore. The opposite end of the bore is slightly enlarged as indicated at 9 to receive the upstanding collar 10, and the casing 5 is joined to this collar by suitable fastening devices such as the screws 11. The collar 10 is integral with the base 12 having a hollow interior 13 below the horizontal wall 14 thereof. Depending from the wall 14 is a hollow neck 15 which terminates inwardly of the bottom of the base. A bore 16 is provided in the neck 15 and includes an enlarged portion 17 defining a shoulder 18. A plunger 19 of insulating material is mounted in the bore 16 and fast to one end thereof is a cap 20. A spring 18 is arranged in the enlarged portion 17 of the bore 16 between the shoulder 18 and the inner end of the cap 20 to thereby urge the plunger 19 outwardly into the dotted-line position of Fig. 2.

Fast to the inner end of the plunger 19 and of a diameter slightly greater than the diameter of said plunger is a contact 21. Mounted on the inner end of the collar 10 is a plate 22 of insulating material carrying a contact plate 23 having a medial opening therein through which the plunger 19 is extended. A conductor 25 is fast to a contact lug 26 on the contact plate 23. When the base 12 is rested on a suitable support, the outer end of the cap 20 also engages this support

and forces the plunger 19 inwardly against the action of the spring 18 and disposes the contact 21 in the full-line position of Fig. 2 whereat it is out of engagement with the contact plate 23. However, when the device is lifted from the support, the spring 18 expands and moves the cap 20 into the dotted-line position of Fig. 2 to thereby move the contact 21 into engagement with the contact 23. Located substantially medially in the extent of the bore 6 is a rib 24 having a central opening 27 therein. The upper edge of the rib 24 is recessed to receive the lower end of a screw socket 28. A washer 29 of insulating material rests on the lower wall of the socket 28 and is engaged by the head of a screw 30 passed through an opening therein and an opening in the lower wall of the socket 28. The screw 30 also extends through the opening 27 and into a tube 31 depending below the rib 24. The screw 30 serves to clamp the socket 28 and the tube 31 in position and the washer 29 insulates the screw from the socket. A conductor 32 extends through an opening 33 in the rib 24 and is fast to the socket 28. In the tube 31 is a plunger 34 which rests on the contact 21 and said plunger is slidable in said tube. The plunger therefore follows the contact 21 as it moves downwardly with the plunger 19 and when the contact 21 engages the contact strip 23 circuit is closed to the screw 30 through the plunger 34 and tube 31. An igniter element 35 includes a screw base 36 having a contact 37 at the lower end thereof which, when the screw base is arranged in the screw socket 28, engages the head of the screw 30. One end of the electrical unit in the element 35 is connected to the contact 37 and the other end thereof is connected to the conductive portion of the screw base 36. The conductors 35 and 32 are directed to a suitable source of electric current but circuit to the element 35 is not closed until the contact 21 engages the contact plate 23. This contact engages this contact plate 23 as soon as the device is lifted from the support on which it is rested. However, should the device be inverted or should it be inadvertently knocked over, the plunger 34 will move through the tube 31 and will disengage the contact 21 to thereby open the circuit, and this arrangement provides a safety to thereby prevent inadvertent operation of the igniter.

Since the element 35 is detachably arranged in position with the peripheral edge thereof in the enlarged portion 7 of the bore 6, installation and removal thereof is facilitated and consequently should the element burn out it may be readily removed and replaced. Furthermore, the

switch arrangement provided is positively operated to thereby insure good contact. Furthermore a safety device is provided which will prevent inadvertent operation, but it is to be understood that this safety device may be omitted and direct, yieldable connection established between the contact 21 and the screw 30. These advantages are inherent in the illustrated structure, but it is to be understood that changes and alterations might be made therein and I therefore do not wish to be limited to the precise details set forth but desire to avail myself of such changes and alterations as fall within the ambit of the following claims:

15 I claim:

1. An igniter including a casing, an igniter element removably mounted at one end of said casing, a switch structure at the other end of said casing adapted to control operation of said element and including a spring-urged plunger having a contact at one end thereof, a contact member engageable with said contact when said plunger is moved in one direction by the spring acting thereon, a sleeve electrically connected to said element, and a member slidably mounted in said sleeve and resting on said plunger and establishing electrical connection between said sleeve and said plunger, said member being movable relative to said plunger when said igniter is inverted to open the circuit between said sleeve and said plunger to prevent inadvertent operation of said igniter.

2. An igniter including a casing having an igniter element at one end thereof, a plunger at the other end of said casing, a contact plate, a contact carried by said plunger, a spring acting on said plunger to urge the same in one direction to move said contact into engagement with said contact plate to close a circuit to said igniter element, and a follower for said plunger slidably mounted in said igniter and releasably engaging said plunger and adapted to open the circuit to said element to prevent inadvertent operation thereof when said igniter is upset.

45 3. An igniter including a casing, an igniter element at one end of said casing, a switch structure at the other end of said casing for controlling the operation of said element, and means including a member for electrically connecting said switch structure and said element, said member being movable relative to said element and releasably engaging said switch structure and being adapted to disengage said switch structure to open the electric circuit between said switch structure and said element when said igniter is upset.

4. An igniter including a casing having an igniter element at one end thereof, a contact plate at the other end of said casing, a spring-urged plunger having a contact at one end thereof adapted to engage said contact plate when said plunger is moved by the spring acting thereon, and a freely slidable member connecting said contact to one terminal of said element, said member being movable independently of said contact and plunger whereby circuit to said element may be opened by disengagement of said member from said contact when said igniter is upset to thereby prevent undesired operation of said element.

5. An igniter including a casing having an igniter element at one end thereof, a plunger at the other end of said element, a spring acting on said plunger to urge the same outwardly with respect to said casing, a contact plate, a contact carried by said plunger and engageable with said contact plate when said plunger is moved by the spring acting thereon, a guide, a member freely slidably in said guide and having one end thereof rested on said contact whereby circuit may be closed to said element from said contact through said member and guide, said member being movable from engagement with said contact when said igniter is upset to open the circuit to said element to prevent undesired operation of said element.

6. An igniter including a casing having a bore therein and a rib extending across said bore, a socket mounted on one side of said rib and in said bore, a tube in said bore on the other side of said rib, means extending through said rib to secure said socket and said tube in said casing, an igniter element mounted in said socket, a plunger slidably mounted at the end of said bore opposite said socket, a spring acting on said plunger to urge an end thereof outwardly of the adjacent end of said casing, a contact plate, a contact carried by said plunger and disengaged from said contact plate until said plunger is moved by the spring acting thereon to have an end thereof extending beyond the adjacent end of said casing, and a member slidably mounted in said tube and releasably engaging said contact to be movable therewith, said member disengaging said contact when said igniter is upset to interrupt electrical connection between said tube and said contact to prevent undesired operation of said igniter element.

FRED R. BELT.
